REVOLVER CLIP

John A. Woodhead, Swarthmore, Pa.

Application March 27, 1934, Serial No. 717,615

2 Claims.

(Cl. 42—89)

This invention has reference to what may be termed a revolver clip, the same being designed to receive a plurality of bullets and to facilitate positioning such bullets for loading the magazine of a revolver.

Briefly the invention consists of a flexible device consisting of a series of pivoted units each provided with a clip for engagement with the shell of a bullet, the whole adapted to be disposed about the revolver in a position to substantially align the bullets with the bullet receiving chamber of the magazine for the purpose of effecting a quick and efficient loading of the revolver.

The invention together with its objects and advantages will be best understood from a study of the following description taken in connection with the accompanying drawings wherein:

Figure 1 is a side elevational view of a revolver illustrating the application of the invention.

Figure 2 is a plan view of the clip, the same being shown in a rolled position.

Figure 3 is an elevational view of the clip with the bullets in position thereon.

Figure 4 is a plan view of the clip.

Figure 5 is a sectional view taken substantially at right angles to Figure 4 and on the line 5—5 of Figure 4.

Figure 6 is a plan view of one of the members of the clip.

Figure 7 is an elevational view taken at right angles to Figure 6, and

Figure 8 is a detail sectional view taken substantially on the line 8—8 of Figure 6.

Referring to the drawings by reference numerals it will be seen that the clip indicated generally by the reference numeral 10 comprises a series of somewhat identical members including the members 11 and an end member 11'. Each of the members 11 comprises a plate of metal or other suitable relatively rigid material having disk like end portions 12 and 13 connected by a narrow web portion 14, the member 11' has the parts thereof in substantially the same plane while the members 11 differ from the member 11' in that as clearly shown in Figure 7 the disk end 13 of each member 11 is in a plane offset from the plane of the end disk 12, the web 14 being offset downwardly where it merges with the end disk 13.

The end disk 12 of each member is provided with a spring clip 15 connected thereto through the medium of the web 16 integral at one end with the clip 15 and at a relatively opposite end with the peripheral edge of the disk end 12.

Also each of the members 11, 11' have the disk

end 13 thereof provided with an upstanding stop lug 17.

The members 11 and 12 are joined together so that the disk end 12 of each member 11 overlaps the disk end 13 of the next adjacent member, and the lapped and overlapping parts of these members are pivoted together through the medium of rivets or other suitable pivots 18 as clearly shown in Figure 5.

The clips 15 are of substantially U-shaped form and the clip associated with the member 11' has one side thereof merging into a reverse bend 19 to provide a finger piece to initiate release of the clip associated with the member 11' relative to the bullet, and to facilitate release of the successive spring clips 15.

In actual practice the head ends of the shells 20 are engaged with the clips 15 in a manner

thought to be clear in the drawings and in loading the revolver 21 the magazine 22 thereof is first

placed in the loading position shown in Figure 1 and the clip 10 carrying the bullets is then

placed about the body of the gun in the position

shown in Figure 1 in a manner to place the shells 20 in proper alignment with the shell receiving

chambers or bores of the magazine 22. The clip

with the shells carried thereby is then moved

forwardly to introduce the noses of the bullets

into the proper bores of the magazine, and when

the bullets have been forced inwardly of the bores

until the bottoms or free ends of the clips engage

the adjacent end face of the cylinder, the end

clip is first removed. In removing this clip the

operator with one finger engaging the return

bend or hand piece 19 of the clip associated with

the member 11' releases this clip from the first

shell 20 and then with a movement at right an-

gles to the revolver, the clip is stripped from the

shell. As the clip is thus stripped from the

shells the latter of their own accord fall into

place without any effort on the part of the operator.

With this connection it will be also apparent

that the stops 16 cooperate with the connecting

webs of the several elements of the clip for lim-

iting swinging movement of each of the elements

as the clip is pulled free from the shell, it being

understood that as each shell is released the cyl-

inder 22 continues its revolving movement about

its own axis.

Having thus described my invention, what I

claim as new is:

1. In a device of the character described, a

series of articulated links, each link being formed

from a single blank of metal cut, shaped and di-

5 mensioned to provide a platelike body portion having its respective opposite ends of substantially disk shape and a narrow intermediate portion connecting said ends and having its longitudinal edges spaced inwardly with respect to the peripheral edges of said disk-shaped ends; one of said disk-shaped ends having integral with a peripheral edge thereof a narrow web projecting at substantially right angles to the longitudinal 10 median of the plate and also disposed in a plane substantially at right angles to the plane of the plate, and a cartridge clip integral with said web, and the other of said disk-shaped ends having integral with a peripheral edge thereof and 15 at a point substantially diagonal to the longitudinal median of the plate an integral projection disposed angularly on the side of the link opposite to said web and forming a stop adapted to abut the side edge of the intermediate portion 20 of an adjacent link for limiting the movement of the links from that of a substantially straight position to that of a substantially circular position.

2. In a device of the character described, a series of articulated links, each link being formed from a single blank of metal cut, shaped and dimensioned to provide a platelike body portion

having its respective opposite ends of substantially disk shape and a narrow intermediate portion connecting said ends and having its longitudinal edges spaced inwardly with respect to the peripheral edges of said disk-shaped ends; 5 one of said disk-shaped ends having integral with a peripheral edge thereof a narrow web projecting at substantially right angles to the longitudinal median of the plate and also disposed in a plane substantially at right angles 10 to the plane of the plate, and an arcuate shaped cartridge clip integral with each of said webs, said cartridge clip associated with the end link of said device having a hook shaped integral finger piece formed as an extension of one end 15 of said clip to facilitate manipulation of the device and for moving the link from a substantially circular position to a substantially straight position in a clockwise direction for successively disengaging the cartridge clips from the cartridges, 20 means pivotally connecting the links in overlapping relation and stops projecting angularly from certain of the links for engaging the side edge of the intermediate portion of an adjacent overlying link to limit the movement of the link from 25 a straight to a circular position.

JOHN A. WOODHEAD.
